INERTIA OPERATED PIVOTED BOLT LOCK

Val A. Browning, Ogden, Utah, assignor to J. M.
& M. S. Browning Company, Ogden, Utah, a
corporation of Utah

Application September 27, 1944, Serial No. 555,949

7 Claims. (Cl. 89—182)

1

This invention relates to improvements in firearms, and particularly to self-loading, recoil-operated firearms.

It is an object of this invention to provide a self-loading, recoil-operated firearm which has a new and improved construction and a novel recoil self-loading operation and wherein the unlocking of the breech block from the barrel is caused to occur automatically during the recoil stroke of the barrel through the action of various forces at play with the result that the barrel and breech block are unlocked at a proper and safe moment irrespective of the character and intensity of the charge employed and promptly following the establishment of such proper and safe condition, and wherein such operation is effected without the use of abutments or stops for positively arresting the rearward movement of the barrel or the use of positively actuated means for disengaging the breech block from the barrel at a fixed point.

With my improved arrangement, some of the more severe shocks inherent in previous arms of this type are eliminated so that the "kick" on the operator's shoulder and the shock to which the parts are subjected are greatly reduced, permitting of the use of lighter parts and a greater freedom in the selection of the materials of which the parts are made. Wear and tear on the firearm and its operating mechanism are greatly reduced. Furthermore, with my improved arrangement, the barrel recoil is materially shortened which permits the use of a shorter receiver, a material improvement in the appearance of the firearm, and a substantial reduction in weight.

A further aim of the invention is to provide in a firearm of this type a new and improved arrangement for transferring the successive cartridges from the magazine to the firing chamber and, particularly, to provide an arrangement wherein the magazine may be loaded at all times when the breech block is forward in closing position without the necessity of pushing a manual button or other instrumentality of the type usually employed on firearms of this character, and wherein the carrier is simplified and its operation is improved.

It is a further object of the invention to provide a new and improved firing mechanism for firearms which is simple in construction and highly efficient in operation.

Other objects will be in part obvious and in part pointed out more in detail hereinafter.

The invention accordingly consists in the features of construction, combination of elements

and arrangement of parts which will be exemplified in the construction hereafter set forth and the scope of the application of which will be indicated in the appended claims.

5 The following description will be more readily understood by referring to the accompanying drawings, in which similar reference numerals refer to similar parts, and in which:

10 Figure 1 is a side elevational view of an automatic, recoil-operated firearm embodying the present invention;

15 Fig. 2 is an enlarged sectional view taken generally longitudinally and vertically through the firearm, with parts of the operating mechanism shown in side elevation;

20 Fig. 3 is a like sectional view, of a still greater enlargement, showing the operating mechanism of the firearm illustrated in Fig. 1 when the same is in firing position, the rear and forward ends of the firearm being omitted;

25 Fig. 4 is a view similar to Fig. 3, in which the parts are in a position which they occupy during an intermediate stage in the recoil stroke, and more particularly illustrating the barrel in the position which it occupies toward the end of its recoil stroke and the breech block in a position where it is unlocked from the barrel and is continuing its recoil movement;

30 Fig. 5 is a view similar to Fig. 3 but looking at the other side of the firearm and showing the relative positions of the parts when the breech block has almost reached the end of its recoil movement and at which time the carrier is in depressed position, as shown, to receive a new cartridge from the magazine;

35 Fig. 6 is a view similar to Fig. 5 but showing the carrier latched in depressed position and the breech block locked in retracted position, a condition which takes place when the firearm has been fired and the magazine is empty, or when the breech block is manually moved to its retracted position while there are no cartridges in the magazine;

40 Fig. 7 is a view similar to Fig. 3 but shows the positions which the parts assume while the breech block is moving rearwardly from the position shown in Fig. 5 to the extreme end of its recoil stroke;

45 Fig. 8 is a view similar to Fig. 7 illustrating the relative positions of the parts when the breech block is approaching the forward end of its return movement and just prior to the locking of the barrel and breech block;

50 Fig. 9 is a plan view, partly in cross section,

taken on the line 9—9 of Fig. 5 and looking in the direction of the arrows;

Fig. 10 is an elevational cross sectional view taken on the line 10—10 of Fig. 3 and looking in the direction of the arrows;

Fig. 11 is an elevational cross sectional view taken on the line 11—11 of Fig. 3 and looking in the direction of the arrows;

Fig. 12 is a perspective view showing the construction of the link;

Fig. 13 is a side view of the closure plate 170, the right hand extractor 55 and the operating handle 19 being shown in phantom; and

Fig. 14 is a top edge view of the closure plate and a portion of the breech block.

Before describing my improved firearm in detail, a general statement as to its construction and mode of operation will first be given. My improved firearm has a frame here shown in the form of a receiver, a barrel provided with a barrel extension mounted for reciprocation in the receiver, a breech block provided with means (such as a locking block) for locking the breech block to the barrel extension, an inertia instrumentality comprising an inertia member or block connected to the locking means and arranged to automatically disengage the latter from the barrel during the recoil stroke of the barrel and before the barrel reaches its rearmost point of recoil, and means comprising a recoil spring for resisting recoil movement of the barrel and exerting a resistance of sufficient magnitude to yieldingly stop the barrel in its rearward recoil movement and then return the barrel to its firing position. When the firearm is fired, the rearward pressure of the gases resulting from the explosion forces the barrel, the breech block in locked relation to the barrel extension, and the inertia instrumentality rearwardly with an accelerating movement through a very short distance and then the parts, due to the action of the recoil spring, undergo a decelerating recoil movement during which time the breech block is automatically unlocked from the barrel extension due to the momentum of the inertia instrumentality. After the breech block is thus unlocked, the recoil resisting means will yieldingly stop rearward movement of the barrel in space (that is, without the barrel striking any fixed stops or abutments), and the recoil spring will then advance the barrel to its firing position while the breech block and the inertia block continue their recoil movement. An action spring then returns the breech block and inertia member to their forward positions where the breech block is automatically locked to the barrel extension. The point at which the barrel is stopped in its recoil movement is variable (this being permissible as the barrel, in its rearward movement, is not brought against a fixed abutment or the like), the extent to which the barrel moves rearwardly being largely dependable upon the character and intensity of the charge employed. Consequently, any standard shell may be employed in the firearm as variations in the explosive intensity of shells within the standard range are automatically provided for, and no manual adjustment of the firearm is necessary.

The firearm is also provided with a carrier for transferring the shells, one by one, from the magazine to a position where they may be forced into the firing chamber by the advancing breech block and, in accordance with the present invention, this carrier is normally in a raised position so that it is out of the way which will

permit the manual insertion of the shells into the magazine without the annoyance or inconvenience of manually moving the carrier or operating buttons or the like. Means are provided whereby, when the firearm is fired, the carrier is automatically lowered to cartridge receiving position and then raised into a position where the shell thereon may be fed by the breech block into the firing chamber.

By referring to the drawings, it will be noted that the present invention is illustrated as embodied in a firearm comprising a barrel 10, a frame or receiver 11, and a stock 12. The barrel is of usual construction and is provided at its rear end with a barrel extension 13 and a cartridge chamber 14. The barrel extension extends into an opening 39 in the forward end of the receiver. The barrel is further equipped with a barrel guide ring 15 which is slidably mounted on the cylindrical magazine 16. The receiver or frame 11 may be of any suitable construction and is here illustrated as a one-piece member which is rounded off at its top rear surface to give the firearm an improved, streamlined appearance. The receiver is provided with the usual ejection opening 17 in one side face thereof and a slot 18 extending from the rear edge of said opening to accommodate the operating handle 19. The magazine 16 is permanently secured to the front end of the receiver as at 20 by screw threads or other suitable attaching means.

The rear of the receiver is preferably equipped with a threaded extension 21 which serves as a mounting for the inertia member tube 22, which fits within the bore 23 of the stock 12. The inertia member tube is closed at its rear end by a suitable plug 24 or the like, which is provided with an internally threaded opening 25 for accommodating the stock bolt 26, preferably in the manner shown in Fig. 2. The stock bolt 26 extends through a smaller opening 27 in the stock and has an enlarged head 28 abutting the inner end of a larger opening 29 in the stock. Through the instrumentality of the stock bolt the stock is held in proper position on the receiver.

Between the barrel guide ring and the opposed face of the receiver a recoil spring 39 is provided, together with one or more friction rings 32—32 which serve to resist the recoil movement of the barrel and to restore the barrel to firing position following recoil. The friction rings 32—32 may be of any suitable construction and are here illustrated as comprising split collars 33—33 surrounded by suitable retainer springs 34—34.

In this particular invention the recoil spring 39 and the friction rings 32—32 are of such construction that they collectively provide sufficient resistance to the recoil movement of the barrel to stop its rear movement in space within the receiver, that is without the use of abutments or the like against which the barrel may strike.

Within the magazine tube 16 a suitable magazine spring 35 is mounted for advancing the shells in the magazine rearwardly in the conventional manner for automatic loading of the firearm. The forward end of the magazine tube 16 is threaded as at 36 for accommodating the magazine cap 37 which, with the usual fore-end 38, holds the barrel in mounted position with respect to the receiver.

In the opposite side walls of the receiver, at

an intermediate point in the height thereof, a pair of opposed grooves 40-40 are provided which constitute slide tracks for the barrel extension and breech block during their reciprocatory recoil and return movements. Laterally projecting flanges 41-41, formed on the lower forward portion of the barrel extension, are slidably mounted in the grooves 40-40. The breech block 44 is provided with laterally extending flanges 45-45 which are likewise slidably mounted in the grooves 40-40 in the receiver. The breech block may be of any suitable construction, but in the illustrated form of the invention it is provided with a centrally disposed vertical recess 46 adapted to accommodate the locking block 47.

One of the lateral faces of the recess 46 of the breech block 44 is provided with an arcuate slot 48 which slidably accommodates a correspondingly shaped arcuate lug 49 on the adjacent face of the locking block. The center of the arcuate slot and lug in the present illustration is located outside of the body of the locking block and in such position as to give the desired movement of the locking block relative to the breech block.

The forward portion of the breech block is provided with a central opening 49' for accommodating the firing pin 50. The opening 49' is enlarged, as at 51, and constitutes a seat for the forward end of the firing pin spring 52 which is preferably mounted as shown and which, at its opposite end, abuts the flange 53 formed integrally with the firing pin. The intermediate portion of the firing pin is accommodated in the central slot 54 in the locking block 47, and its rear end is slidably mounted in a suitable opening therefor in the retaining plate 55. The breech block is further provided with suitable extractors 56-56 on the opposite sides thereof, of conventional construction.

The barrel extension 13 has a longitudinally extending groove 130 therein in position to accommodate the extractor 56 located on the adjacent side of the breech block. At the rear of the barrel extension and at the end of the groove 130 is the ejector 131 which is of conventional construction and which serves in cooperation with the extractors to eject the spent cartridge. In addition, the barrel extension is provided with the locking opening 132 which is adapted to receive the projecting end of the locking block in such manner as to lock the breech block and the barrel extension in cooperative relationship. The locking opening 132 has its rearward lock-engaging face 133 formed on an arc which corresponds to the arc determining the shape of the face 134 on the locking edge of the locking block. This arc, however, is struck from a center somewhat above the center of the arc determining the movement of the locking block 47, whereby a new and improved locking action results. This construction causes a smoother unlocking action between the breech block and barrel.

In the bottom of the breech block there is a centrally disposed slot 57 which accommodates the locking block latch 58, which is pivoted to the breech block at 59. This latch is preferably constructed as shown and has an extension 60 which bears upon the compression spring 61 mounted in the recess 62 of the breech block. The latch extends toward the rear of the firearm and has a locking end portion 63 adapted to engage the shoulder 64 of the locking block when the locking block is moved to unlocked position (see Figure 4).

The lower rear corner of the locking block is

pivoted at 65 to a link 66 which extends rearwardly and terminates in a suitable pivot member, such as 67, for pivotal connection to the inertia member 68. The particular pivot connection shown permits assembly and disassembly by merely sliding the link 66 laterally relative to the inertia member 68. As more particularly shown in Fig. 2, the inertia member 68 is slidably mounted in the inertia member tube 22 and also has abutting engagement with the action spring 69. The opposite end of the action spring is seated against the plug 24 which closes the rear end of the inertia member tube 22. The inertia member 68 is further equipped with the rearwardly projecting extension 98 which has sufficient length to abut the plug 24 in the extreme rearward position of the inertia member to form an ultimate stop for the recoil movement of the inertia member and breech block. A cushioning washer or disc 150 of felt, fiber, rubber, or other suitable material is preferably placed on top of the plug 24.

The firing mechanism here illustrated comprises a trigger plate 70 having a central slot 72 therein and equipped with a suitable trigger guard 71 extending from the bottom thereof. The trigger 73 is pivoted on the pin 74 and has an upwardly extending end 75 pivoted at 76 to the counterbalancing link 77. The other end of the link 77 is pivoted as at 78 to the upper arm of the sear 79 which is mounted for oscillatory movement around the axis of a pin 80. The pin 80 extends through an opening in the sear and projects on opposite sides thereof and is accommodated in the semi-circular bearings formed in the extensions 81-81 on the upper face of the trigger plate.

The lower end of the sear extends downwardly and presents a portion 82 in spaced and opposed relationship to a portion 83 of the trigger. These portions 82 and 83, respectively, are provided with recesses, as shown in Fig. 3, in which the opposite ends of a compression coil spring 84 are mounted. The lower arm of the sear is provided with a hammer-engaging tooth 85 which coacts with the hammer notch 86 on the hammer 87 for holding the hammer in cocked position. The hammer is pivotally mounted on a pin 88 carried by the lugs 89-89 extending upwardly from the forward portion of the trigger plate. The upper arm of the sear is provided with a tooth or hook 90 for engaging a cooperating tooth 91 on the hammer in the event that the trigger is held pulled after firing a shot.

Extending through the hammer adjacent its pivot is a pin 92 equipped with parallel diametrically disposed holes 93 which accommodate the forward ends of the main spring guide rods 94-94. These rods are each provided with an integral flange 95 adjacent their forward ends to limit their forward movement with respect to the pin 92 and to provide abutments for the forward ends of the main springs 96-96. The pin 80, which extends through the intermediate portion of the sear 79, is likewise provided with parallel diametrically extending holes 97-97 which slidably accommodate the rear ends of the main spring guide rods 94-94.

The trigger plate may be attached to the receiver by pins 136 located in longitudinally extending grooves 135 provided in the side faces of the trigger plate and which cooperate with complementary semi-circular grooves provided in the opposed faces of the receiver. When the firing mechanism is in proper position, the co-

operating grooves referred to are adapted to accommodate retaining pins 136—138 which securely hold the parts in proper relationship. The retaining pins may be inserted from the rear and held against accidental displacement by means of the stock which covers the ends of the pin openings when the firearm is fully assembled.

A carrier 100 is also mounted in the lower portion of the receiver and preferably comprises a pair of spaced arms 101—101 pivoted on the carrier pin 102 which has its opposite ends mounted in the spaced side walls of the receiver. Suitable bushings 120—120 are provided so as to maintain the carrier in a proper centralized position in the receiver. The forward ends of the arms 101—101 of the carrier 100 are connected by means of a cross pin 103 and the rear ends thereof are connected by a cross pin 104. The carrier arms 101—101 are so constructed and arranged that they straddle the upper portion of the firing mechanism and have a sliding and guiding contact with the lugs 89—89 on the forward end of the trigger plate. These lugs guide the carrier in its vertical movements and prevent lateral movement thereof so that the pivot pin 102 is relieved of torsional strains.

Mounted on the rear pin 104, between the arms of the carrier, is a pair of locking pawls 105—105 which are spaced apart to provide a central space for accommodating the carrier-depressing lever 106. The locking pawls 105 and the carrier-depressing lever 106 are all pivotally mounted on the pin 104, and the locking pawls are held in operative positions by means of the ends 107—107 of the coil springs 108—108, respectively. The ends 107 extend into the slots 109 on the outer lateral faces of the pawls, whereby through the depressing action of the springs the pawls are held in operative position and at the same time a downward pressure is exerted on the pin 104. This downward pressure on the pin 104 causes the opposite end of the carrier to be normally urged in an upward direction. The carrier-depressing lever 106 has its upper end extended sufficiently to occupy the space constituting the central slot 110 in the link 66, and for engagement, at the proper moment, with the shoulder or cam face 111 located at the forward end of the slot 110.

The lower end of the carrier-depressing lever is formed to constitute a cam 112 which in certain positions is adapted to engage and bear upon the upper face 113 of the bearing block 114 slidably mounted in a groove 115 in the upper face of the trigger plate. Forward movement of the bearing block 114 is limited by means of pin 116 and the block is normally urged in contact with the pin by means of the compression spring 117.

As particularly illustrated in Figs. 5, 6 and 9, inclusive, the inner face of one wall of the receiver, at the location adjacent the exit of the magazine, is provided with a recess 121 in which is pivotally mounted the carrier lock and cartridge stop member 122. This member may be constructed in the manner illustrated in the drawings, and the pivot 123 therefor extends vertically as shown in Fig. 5. The outer face of the member 122 is provided with a recess 124 for accommodating the conical compression spring 125 which also bears on the face of the receiver recess and acts to urge the associated end of the carrier lock and cartridge stop member 122 outwardly into the space of the receiver. The forward end of the member 122 constitutes a stop for the cartridges contained in the magazine and

the rear end of the member 122 constitutes a lock for holding the carrier in depressed position under certain conditions. The arrangement, relation, and movements of the carrier and the carrier lock and cartridge stop member 122 are such that when, and only when, the carrier is in the depressed or cartridge receiving position shown in Figs. 5, 6 and 9 and the magazine is empty of cartridges, the rear of the member 122 overlies the adjacent arm 101 of the carrier so that the carrier is locked down. In all other positions of the carrier, the arm thereof lies in the path of inward movement of the rear end of the member 122 so that that end will bear against the outer face of said arm and thus the member 122 is held in a position where the forward end thereof is in cartridge stop position. It is understood, of course, that when a cartridge is delivered from the magazine onto the carrier, the flange on the rear end of the cartridge will force itself between the receiver wall and the member 122, and thus force the member to the full line position shown in Fig. 9. The forward end of the member 122 is resilient and yieldable whereby it is free to move towards the wall of the receiver during the insertion of cartridges into the magazine and to spring back to cartridge stop position after each cartridge has been so inserted. In order to manually disengage the member 122 from the carrier when the parts are in the position shown in Fig. 6, a button 140 is conveniently presented on the outside of the receiver.

The operation of the illustrated embodiment of the invention will now be described and, as a starting point, it will be assumed that the firearm is in the firing condition shown in Fig. 3, a shell is in the firing chamber, and shells are in the magazine. When the parts are in these positions, the action spring 69, through its forward pressure on the inertia block 68, forces the inertia block, the link 66, and, through the locking block 47, the breech block 44 together so that these parts act as an integral mass to close the breech and maintain the firearm in locked condition when the same is fired. The distribution of the engaging faces 134 and 133 of the locking block and barrel extension 13, respectively, is such as to bring about a wedging action tending to press the breech block against the head of the cartridge in the firing chamber and, in addition, to take up wear which might develop between the parts and which otherwise would cause undesirable head space. Upon pulling the trigger, the hammer 87 is released from the sear 79 so that the hammer is free to swing (under the influence of the main springs 96) from the full line position to the dotted line position shown in Fig. 3 thus striking the firing pin 50 and causing explosion of the shell within the firing chamber. As a result of the explosion, the power gases generated act against the forward face of the breech block and cause the barrel, the breech block, the link, and the inertia member to move rapidly rearwardly in recoil. At the instant of firing, the pressure of the gases builds up very rapidly so that the barrel and the breech block in locked condition are driven backwardly through an extremely small distance with an accelerating movement and then, as the pressure of the gases decreases, and because of the resistance offered by the recoil spring 30 and associated parts, continued recoil movement of the barrel is progressively retarded and decelerated. During said relatively short accelerating portion of the recoil movement, the link 66 and the inertia member

68, due to their mass and tendency to remain in a state of rest, will move rearwardly with the breech block acting in the nature of an integral mass so that, during such portion of the recoil movement, the locking block 47 will be securely retained in locked relation to the barrel.

The recoil movement of the barrel causes a corresponding rearward movement of the barrel guide ring 15 as well as the friction rings 32 and also a compression of the recoil spring 30. The 10 resistance of the recoil resistance means, including the spring and the friction rings, is such, as previously indicated, that the recoil movement of the barrel will be rapidly decelerated after it has reached its highest recoil velocity and rearward movement of the barrel is yieldingly terminated in space at a variable point depending upon the character and intensity of the charge and then the recoil spring will return the barrel to its forward or normal position.

During the initial portion of the decelerating recoil movement of the barrel, the breech block, being connected to the barrel, tends to decelerate therewith while the inertia member tends to continue at its then attained velocity so that the inertia member will exert a rearward pull on the locking block and draw it downwardly out of locking engagement with the barrel extension. Unlocking of the locking block from the barrel starts as soon as the recoil movement of the barrel begins to decelerate, and the unlocking is entirely effected before the barrel has reached its rear-most position. During downward unlocking movement of the locking block, the angular locking faces 133 and 134 slide on one another so that the disengagement takes place gradually. This permits the breech block, due to its momentum, to move faster than the decelerating barrel so that the breech block may be gradually picked up by the inertia member resulting in a smooth and effective action. Furthermore, during the unlocking period, the breech is being gradually opened, that is, the breech block is moving gradually away from the firing chamber and it is at this time that the extractors 56 pick up the empty shell, this being of advantage in that this primary extraction of the empty shell is gradual as distinguished from an extremely violent initial extraction which would be apt to rupture or deform the shell.

It is understood that the resistance of the recoil resistance means is of such magnitude as to progressively retard the recoil movement of the barrel after it has reached its highest velocity and then yieldingly bring the barrel to rest, and the inertia instrumentality is of such mass that its momentum, during the decelerating movement of the barrel, is sufficient to unlock the locking block from the barrel extension and, while the point at which the unlocking action takes place will vary somewhat depending upon the intensity of the charge, the relation of the operating parts is such that such unlocking cannot occur until after deceleration of the barrel starts whereby the unlocking of the breech block from the barrel occurs only at a time when it is entirely safe to unlock.

The breech block, link, and inertia member continue their movement to the rear under the influence of their own momentum and against the action of the action spring. Such recoil movement of the breech block will be terminated when the extension 98 of the inertia member engages the cushioning disk 150 on the closing plug 24, whereupon the action spring (the barrel in

5 the meantime having been returned to firing position) will advance the inertia block and breech block to their forward position so that the firearm is again in the condition shown in Fig. 3 ready to be fired.

It will thus be seen that, with my improved construction, cartridges having charges of various character and intensity may be fired in the firearm, as previously stated, without making any adjustments. As the recoil movement of the barrel is yieldingly terminated in space, and in the absence of any abutments or stops therefor, the extent of the kick on the shoulder of the operator is reduced and the operating parts are relieved of excessive shocks and strains. It is clear, without further explanations, that the advantages and objects recited in the opening paragraphs of the specification are accomplished with the structure, the operation of which has just been described.

20 The rearward movement of the breech block and the simultaneous forward movement of the barrel extension cause an extraction of the spent shell from the firing chamber by virtue of the fact that the flange of the cartridge is engaged by the extractors 56, 56 mounted on the breech block. When the relative movement between the breech block and the barrel extension has progressed to the point where the flange of the cartridge is brought into engagement with the ejector 131 carried on the barrel extension, the spent cartridge is ejected laterally through the ejection opening 17. During the rearward movement of the link 66, the shoulder 111 thereof engages the hammer 87 and pivots the hammer backwardly to its cocked position.

25 Continuing the description of the operation of the firearm, particularly in connection with the carrier, as previously stated, when the firearm is in firing condition, as shown in Fig. 3, the forward end of the carrier 100 is in an elevated position so that cartridges may be inserted in the magazine. In this position, the springs 108 resiliently maintain the forward portion of the carrier up against the bottom of the breech block. Furthermore, in this position of the carrier and, in fact, in all other positions thereof (except when the carrier is in depressed or cartridge receiving position shown in Fig. 6) and during the movement of the carrier up and down, the rear end of the carrier lock and cartridge stop member 122 bears against the outside face of the right hand arm 101 of the carrier 100 so that the member 122 is held in cartridge stop position. Upon firing the firearm, the link 66 and associated recoil parts recoil rearwardly as previously described and as the link 66 approaches its rear-most recoil position, the shoulder 111 on the link will engage the upper end of the carrier-depressing lever 106 (see Fig. 5) and rock the same rearwardly so as to cause the cam extension 112 on the opposite end thereof to move downwardly in engagement with the upper face 113 of the bearing block 114. In view of the fact that the cam extension has greater height than the distance between the upper face of the bearing block and the pivot pin 104 when the carrier is in the intermediate position shown in Fig. 4, the continued movement of the carrier-depressing lever will cause the pivot pin 104 to be raised and, consequently, the opposite end of the carrier to be depressed to a position where it may receive a new cartridge from the magazine, as shown in Fig. 5. On continued rearward movement of the link (from the position shown in Fig.

5 to that shown in Fig. 7), the cam extension rides off of the bearing block 114 whereupon the springs 108 are free to raise the forward end of the carrier to the position shown in Fig. 7. In this position, the cartridge just received from the magazine is held in elevated position by the carrier in alignment with the firing chamber. When the carrier is cammed down, as just described, to the cartridge receiving position shown in Fig. 5, the right hand arm 104 thereof is moved below the rear end of the member 122 so that that end may snap over the arm (see the dotted line position of the member 122 in Fig. 9). In the event that the magazine is empty, the member 122 will lock the carrier in the depressed position shown in Fig. 6. In the event, however, that the magazine is not empty, the rear-most cartridge therein, as soon as the carrier is moved to depressed position, will be snapped back onto the carrier by the magazine spring 35, and the head of this cartridge will bear against the rear portion of the member 122 thereby camming the member 122 to the full line position shown in Fig. 9, so that the carrier is free to be raised by the springs 108. In this latter operation, there may be, in some instances, a short period during which the carrier is latched down by the member 122, depending upon the speed with which the cartridge is fed onto the carrier and other factors. During the return forward movement of the breech block, the carrier is cammed downwardly by the breech block from the full elevated position in Fig. 7 to the intermediate position shown in Fig. 3. Also, as the breech block is approaching its normal forward position, the shoulder provided by the rear end of the slot 118 in the link 66 will engage the upper end of the carrier-depressing lever 106 and move the same forwardly and thereby swing the extension 112 to the position shown in Fig. 8. During such movement of the cam extension, it will engage and move the bearing block 114 backwardly until it clears the same and then the block is snapped forwardly by the spring 117.

As previously indicated, when the last cartridge is fired, there being no more in the magazine, the breech block will be automatically locked in its recoiled position as shown in Fig. 6. In this position of the parts, the member 122 locks the carrier in depressed position and the locking pawls carried on the pin 104 at the rear end of the carrier are disposed in a position where they engage the shoulder 160 on the underside and adjacent the forward end of the link 66. The locking pawls engage in the notch 160 upon initial forward movement of the breech block and the link. When it is desired to close the firearm, that may be accomplished by manually pushing the button 140 inwardly so as to move the forward end of the member 122 into cartridge stop position and the rear end of the member 122 out of locking relation with the carrier. When the carrier is thus unlocked, the forward end thereof will move upwardly under the influence of the springs 108, thereby disengaging the pawls 105 from the notch 160 of the link 66 whereupon the breech block is free to be moved forwardly by the action spring 69. The action spring, acting through the link 66 and the pawls 105, assists the carrier springs 108 in raising the forward end of the carrier, and this may also occur when there is a cartridge in the magazine and the cartridge, when expelled therefrom, moves the rear end of the member 122 out of locking relation to the carrier.

It is noted that with the construction described, the barrel has a relatively short recoil stroke and this, together with the relatively short breech block, permits the use of a receiver of minimum length with a consequent reduction in size and weight of the firearm. This reduction in length also permits the upper rear portion of the receiver to be rounded off to give a new streamlined appearance to the firearm. The breech block, however, is not of sufficient length to provide a complete closure for the ejection opening 17. In order that the ejection opening may be closed when the breech block is in forward position, a closure plate 170 is slidably mounted on the breech block. As shown in Figs. 11, 13 and 14, the breech block, in its right hand side face, has a longitudinally extending dove-tailed groove 168 in which is slidably mounted a correspondingly shaped rib 171 provided on the closure plate. The groove is open at its rear end so that the rib may be inserted thereinto. The groove 168 has a shoulder 169 at its forward end so as to limit forward movement of the plate with respect to the breech block. The forward end 172 of the plate 170 is bent inwardly so as to engage the forward end of the breech block and thereby limit the extent to which the plate may move rearwardly with respect to the breech block. The plate is made of thin spring metal so that this forward end may be sprung outwardly a sufficient distance to permit the rib 171 to be slipped into the groove 168 and the plate moved forwardly until its end 172 snaps over the forward end of the breech block. The plate is of sufficient length to provide a full length closure for the ejection opening and, at the same time, by virtue of its sliding relationship to the breech block, it may move forwardly and rearwardly by engagement with the receiver and the barrel extension, respectively, during the recoil and return movements of the breech block.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

I claim:

1. In a recoil operated firearm of the character described, a receiver, a barrel carried by and mounted for reciprocation relative to said receiver, a breech block carried by the receiver for reciprocation, locking means carried by the breech block for locking the breech block in operative relation to the barrel, recoil resistance means for progressively retarding the recoil movement of the barrel and yieldingly stopping recoil movement of the barrel in space and then restoring the barrel to its firing position during the interval when said breech block is undergoing its final recoil movement, and an inertia instrumentation associated with the locking means and effective solely by its inertia to completely release the breech block from the barrel with a continuous action during the recoil movement of the latter and before the barrel reaches the rear end of its recoil stroke, said breech block, locking

means, and inertia means being capable of continuing the recoil stroke after the barrel and breech block have been unlocked and while the barrel is being restored to its firing position.

2. In a recoil operated firearm of the character described, a receiver, a barrel carried by and mounted for reciprocation relative to said receiver, a breech block carried by the receiver for reciprocation, locking means carried by the breech block for locking the breech block in operative relation to the barrel, recoil resistance means for progressively retarding the recoil movement of the barrel and yieldingly stopping recoil movement of the barrel in space and then restoring the barrel to its firing position during the interval when said breech block is undergoing its final recoil movement, an inertia instrumentality associated with the locking means for completely releasing the breech block from the barrel with a continuous uninterrupted movement during the recoil movement of the latter and before the barrel reaches the rear end of its recoil stroke, said breech block, locking means, and inertia means being capable of continuing the recoil stroke after the barrel and breech block have been unlocked and while the barrel is being restored to its firing position, and means for restoring said breech block in cooperative locked relation with the barrel after the barrel has been restored to firing position.

3. In a recoil operated firearm of the character described, a receiver, a barrel carried by the receiver for reciprocation, a breech block mounted for reciprocation in the receiver, locking means carried by the breech block for locking said breech block in cooperative relationship with the barrel, recoil resistance means comprising a spring for progressively retarding the recoil movement of the barrel and yieldingly bringing the barrel to rest in space and then restoring the barrel forwardly to firing position, an inertia instrumentality connected with the locking means and operative solely by inertia to completely unlock the breech block from the barrel with a continuous uninterrupted action after the barrel has reached its highest rearward velocity and during the decelerating recoil movement of the barrel, and an action spring behind said inertia instrumentality and normally urging the same forwardly and urging said breech block into locking engagement with the barrel when the latter is in firing position, said inertia instrumentality having such mass that it assists in maintaining the barrel and breech block in locked condition upon firing and during the initial recoil movement of the barrel, and due to its momentum will draw the locking means out of locking engagement with the barrel during the decelerating movement of the latter whereupon the locking means and inertia instrumentality will continue their recoil stroke while the barrel is being restored to firing position.

4. In a recoil operated firearm of the character described, a receiver, a barrel carried by the receiver and mounted for reciprocating movement relative thereto, a breech block carried by the receiver and mounted for reciprocation relative thereto, locking means carried by and movable relative to the breech block for locking the same to the barrel, recoil resistance means for retarding the recoil movement of the barrel and yieldingly terminating the recoil movement thereof in space and then restoring said barrel to its firing position during the interval when the breech block is undergoing its final recoil movement, a

rearwardly extending link connected to said locking means, an inertia member connected to the rear end of said link, and an action spring behind said inertia member, said link and inertia member being of such mass as to completely unlock the breech block from the barrel during the recoil movement of the barrel whereupon the breech block, link and inertia member continue their recoil stroke and while the barrel is being restored to its firing position.

5. In a recoil operated firearm of the character described, a receiver, a barrel carried by the receiver and mounted for reciprocation relative thereto, a breech block mounted for reciprocation in the receiver, locking means carried by and movable relative to the breech block, interengaging shoulders on the locking means and barrel for locking said breech block in operative relation with the barrel, recoil resistance means comprising a spring for progressively retarding the recoil movement of the barrel and yieldingly bringing the barrel to rest in space and then restoring the barrel forwardly to firing position during the interval when the breech block is undergoing its final recoil movement, and an inertia instrumentality connected with said locking means and operative by its inertia to completely unlock the breech block from the barrel after the barrel has reached its highest rearward velocity, said interengaging shoulders being so arranged that during the unlocking operation the breech block may move rearwardly with respect to the barrel.

6. In a recoil operated firearm of the character described, a receiver, a barrel having a barrel extension mounted for reciprocation in the receiver, a breech block carried by the receiver and mounted for reciprocation therein, a generally forwardly facing locking shoulder on said barrel extension, a locking member carried by said breech block for radial movement relative thereto and having a generally rearwardly facing shoulder arranged to engage with said first-mentioned shoulder when the breech block is locked to the barrel extension, recoil resistance means for retarding recoil movement of the barrel and yieldingly terminating the recoil movement thereof in space and then restoring said barrel to its firing position during the interval when said breech block is undergoing its final recoil movement, and an inertia instrumentality associated with the locking member for moving continuously the same to completely unlocked position during the recoil movement of the barrel, said shoulders being inclined rearwardly of the firearm whereby during the operation of unlocking the breech block from the barrel extension, the former will move rearwardly with respect to the latter.

7. In a recoil operated firearm of the character described, a receiver, a barrel, a breech block, locking means for locking said breech block in cooperative relationship with the barrel, said barrel and breech block being mounted for reciprocatory motion relative to the receiver and said breech block having a recoil stroke of predetermined length, said barrel and breech block being arranged to undergo recoil movement while in locked cooperative relationship, means for progressively retarding the recoil movement of said barrel, bringing the same to rest in space before said breech block has completed its recoil stroke, and then restoring said barrel to its firing position during the interval when said breech block is undergoing its final recoil move-

ment, inertia means effective solely by its inertia for actuating said locking means for completely unlocking said barrel and breech block with a continuous action during the recoil movement of the barrel and before said barrel has completed its recoil stroke, and means for restoring said breech block in cooperative locked relationship with the barrel after the barrel has been restored to firing position.
